UNITED STATES PATENT OFFICE.

WILLIAM H. FORCE AND MAXIME O. PARENTEAU, OF SPRINGFIELD, MASSACHUSETTS, ASSIGNORS OF ONE-THIRD TO A. DWIGHT CUTLER, OF SAME PLACE.

MACHINERY FOR AND METHOD OF COVERING HEADS OF EYELETS.

SPECIFICATION forming part of Letters Patent No. 551,079, dated December 10, 1895.

Application filed May 6, 1895. Serial No. 548,220. (No model.)

To all whom it may concern:

Be it known that we, WILLIAM H. FORCE and MAXIME O. PARENTEAU, citizens of the United States, residing at Springfield, Hampden county, State of Massachusetts, have invented a new and useful Improvement in Machinery for and Methods of Covering the Heads of Eyelets, of which the following is a specification.

10 Our improvements relate to dies for combining covers of plastic material with the flanged heads of metallic eyelets and for centering and molding the plastic covers thereon, and have for their object the production 15 of an improved eyelet, together with a reduction in the cost of producing the same.

The invention consists in the combination and construction as hereinafter described, and more particularly pointed out in the claims.

20 Our invention is fully illustrated in the accompanying drawings, in which—

Figure I is a side elevation of two dies removed, the upper in half vertical section and the lower in complete vertical section and seating the eyelet and cover-blank in position to be operated on by the dies. Fig. II is a vertical central section through the closed dies and through the combined eyelet and cover. Fig. III is a plan view of the lower 25 die with a covered eyelet seated therein. Fig. IV is a top plan view of an uncovered eyelet. Fig. V is a side elevation of a covered eyelet, and Fig. VI is a plan view of a plastic blank.

30 The machinery in common use for combining the covers with eyelets consists of a face-die, which operates upon a strip interposed between it and the flange of an eyelet seated in the back die to forcibly punch out the 35 perimeter of the cover and the mouth of the tube. The flanges of the eyelets have to be constructed to withstand the strain of the punching-tool, and the perimeter of the cover and the mouth of the tube, both being left 40 rough from sharp edges of the plastic material, require to be submitted to subsequent finishing processes, greatly enhancing the cost of the product, to obviate all of which we 45 form our dies, which may properly be called.

“molding-dies,” as shown in the much-enlarged drawings, as follows:

The face-die H consists of a dependent cone i, a concentric concavity m at the base of the cone, which concavity is in contour a reverse counterpart of the top of the cover h to be 55 molded, and an annular concentric rim or face o outside of the cavity m and adapted to make a tight joint with a face of the back die. The plastic material, such as celluloid, which is softened by heat and made in the 60 form of a washer u, with its hole approximately the diameter of the mouth of tube a of the eyelet, and its thickness and larger diameter proportioned to provide the requisite stock for just supplying the cover, is laid 65 over the flange b of tube a, raised above the face of back die D, as shown in Fig. I, and when so laid is molded by the descent of the heated face-die H to form, with slight pressure, a cover to the eyelet without a rough 70 edge upon any of its parts, and having a polished surface. As will be seen, the cone i centers the washer first, rendering unnecessary the performance of this operation manually, and then closes the mouth of the tube, 75 while the rim o rests upon the face of the back die to thus form a mold, completely inclosing all of flange b, and one which the washer u flows to fill.

The cone or tapering portion i of the male 80 die must be small enough to enter the opening in the female die and leave a space between said parts for the body of the eyelet, when the dies are closed. The heated die softens the plastic material, which is then 85 easily compressed to shape, and solidifies almost instantly when the heated die is withdrawn.

Although a back die with a plain face to 90 seat rim o of the face-die would be sufficient for ordinary purposes, we prefer to form a mouth or countersink s around the opening for receiving the eyelet in die D of larger diameter than washer u and of a depth just sufficient to bring the upper surface of the 95 washer, when resting on the flange of an eyelet, as shown in Fig. I, flush with the face of die D, as said mouth enables a number of

washers to be carelessly swept by hand over the plate containing a number of back dies to feed the washers to the dies, those not finding lodgement in the mouths resting upon 5 a flush surface, from which they are brushed.

The finished eyelet (shown in Fig. II in section and in Fig. V in elevation) forms the subject-matter of an application, Serial No. 545,876, now pending before the Patent Office, 10 and so forms no part of the invention herein claimed.

Now, having described our invention, what we claim is—

1. The method of covering the heads of eyelets with plastic material, which consists in forming the metallic eyelets and forming plastic washers from which the covers are to be made separately, then inserting a metallic eyelet in a hole in a die, and the washer in a 15 recess in said die around the mouth of the hole, then centering the washer with the metallic eyelet by passing a conical die through said washer and into the eyelet from above, and simultaneously molding the washer and 20 fixing it to the eyelet by means of heat transmitted by the die, all substantially as described.

2. The method of covering the heads of eyelets with plastic material, which consists in 25 forming metallic eyelets and plastic washers separately, assembling the eyelet and washer 30 with the washer in contact with flange or rim

of the eyelet, then molding or forming the washer about the rim of the eyelet by compressing with a heated die while retaining the 35 eyelet by a companion die.

3. The companion dies for covering eyelets, the female die having an opening and an enlarged annular recess around the mouth thereof, and the male die having a conical projection with its point concentric with the center of the opening of the female die, and of such size as to leave a space around said cone for the body of the eyelet when the dies are closed, a concavity around the base of the cone, and 40 an annular concentric rim surrounding this concavity adapted to fit the recess in the female die, all combined substantially as described.

4. The pair of dies for molding heads on 45 eyelets, the male die having a conical end projection and a cylindrical shoulder surrounding and concentric with this projection, and the female die having a chamber to receive the conical projection and larger than 50 the greatest diameter thereof, and a recess around the mouth of said chamber to receive and fit the cylindrical part of the male die, all combined substantially as described.
